UNITED STATES PATENT OFFICE.

OLAUS S. AUGENSEN, OF CHICAGO, ILLINOIS.

PIPE-CLAMP.

No. 799,623.

Specification of Letters Patent.

Patented Sept. 19, 1905.

Application filed March 11, 1905. Serial No. 249,663.

To all whom it may concern:

Be it known that I, OLAUS S. AUGENSEN, a citizen of the United States, residing at Chicago, in the county of Cook and State of Illinois, have invented certain new and useful Improvements in Pipe-Clamps; and I do hereby declare the following to be a full, clear, and exact description of the invention, such as will enable others skilled in the art to which it appertains to make and use the same.

This invention relates to improvements in pipe-clamps, and more particularly has reference to clamps of that character designed for repairing or closing breaks in bursted pipes.

The object of the present invention is the provision of a pipe-clamp the construction of which is such as to enable its expeditious application to bursted pipes when occasion arises for its use and whereby when so applied the clamp will serve to draw together the portions of the pipe adjacent the split or break therein, thus effectually sealing the split and preventing leakage through the bursted portion.

The invention further aims to provide a pipe-clamp which is so constructed as to render the same applicable to pipe-coils and in congested spaces wherein the attachment of repair-clamps of the ordinary type is exceedingly difficult.

With these general objects in view and others, which will appear as the nature of the improvements is better understood, the invention consists, substantially, in the novel construction, combination, and arrangement of parts, as will be hereinafter fully described, illustrated in the accompanying drawings, and pointed out in the appended claim.

In the accompanying drawings, Figure 1 is a perspective view of a pipe-clamp constructed in accordance with the present invention and illustrated in applied position upon a section of a pipe. Fig. 2 is a top plan view thereof. Fig. 3 is a side elevation of the clamp. Fig. 4 is a transverse sectional view on the line 4-4, Fig. 2.

Referring to the drawings, it will be seen that the herein-described clamp comprises a pair of complementary sections 1 and 2, each of which is semicircular in cross-section, as clearly shown in Figs. 1 and 4, and designed to envelop a clamp when the sections are applied thereto. Obviously the sections 1 and 2 may be of any desired length to fulfil the purposes of the invention and effectually cover the ordinary split or break in a pipe,

and when applied to a pipe said sections are arranged at opposite sides thereof, as clearly seen. Thus the sections are diametrically opposite and when under pressure, as will 60 presently appear, serve to bind against the pipe and firmly clamp the same.

As before premised, the present invention aims to provide a clamp of such construction as will enable its speedy application and also 65 permit it being used in congested spaces where the attachment of a repair-clamp of the ordinary type is exceedingly difficult, and to the accomplishment of these ends the sections 1 and 2 are constructed to interlock at one of 70 their edges, but which will enable their ready assemblage and separation to permit application and removal of each section independently of the other. The section 1 therefore is provided with a laterally-projecting rib 3, 75 which extends longitudinally of the body of said section, said rib being deflected at a slight angle to the body of the section, and thereby forming a longitudinal groove 4 between the free edge of the rib and the adjacent side of 80 the body of the section. The rib 3 is designed to enter and lie within a longitudinal socket or recess 5, formed upon the section 2 at the edge of the same which lies contiguous to the edge of the section 1, upon which the rib 3 is 85 located, and said socket or recess is formed by a flange 6, which is a prolongation of the edge of the body of the section 2, said flange being curved to assume substantially semi-circular configuration in cross-section, but 90 having its free edge terminating at a point in rear of the adjacent edge of the body of the section 2. By this construction it will be observed that a space is provided between the free edge of the flange 6 and the pipe to which 95 the section 2 is applied, thus enabling the rib 3 of the section 1 to be readily inserted into the recess 5 when assembling the sections of the clamp upon a pipe. It will also be observed that the inner side of the free edge of 100 the flange 6 is a flat surface and lies parallel with the contiguous edge of the body of the section 2. By this construction the free edge of the flange 6 will enter the groove 4 in assembling the sections, as clearly shown by 105 dotted lines in Fig. 4, and will serve as a hinge or pivot upon which the section 1 will swing, the rib 3 bearing against the inner side of the free edge of the flange 6, and thereby locking 110 the sections together.

To hold the sections 1 and 2 upon the pipe when applied thereto, said sections are pro-

vided at the edges opposite to those upon which the rib 3 and flange 6 are formed with a plurality of perforated lugs 7, the lugs of one section being coincident with the lugs of the other, and fitted in said lugs is a plurality of clamping-bolts 8, the threaded shanks of which are provided with nuts 9. The openings of the lugs 7 in one of the sections, preferably section 2, are polygonal to receive the correspondingly-shaped necks of the bolts 8, and thus hold said bolts against rotation when applying the nuts 9, and the outer surfaces of the sections adjacent to said lugs 7 are also cut away, as at 10, to permit the heads of the bolts 8 and the nuts 9 seating upon the respective lugs.

In use when a pipe has split, the section 2 is preferably first applied to the pipe at a point adjacent to the leak or split, and with a strip 20 of packing 11 to serve as a patch placed over the split or break the section 1 is connected to the section 2 by inserting its rib 3 into the socket or recess 5 of the flange 6, whereupon the bolts 8 are passed through the coincident lugs 7 and the nuts 9 applied to the bolts. As the pressure of the bolts and nuts is exerted upon the lugs 7 the sections are drawn closely together, thereby firmly pressing the packing 11 upon the split portion of the pipe, and, 30 obviously, as the pressure continues the packing is tightly clamped to the split or broken portion of the pipe and leakage effectually stopped. In congested spaces, where the ordinary repair-clamp is difficult of application, 35 the section 1 may be readily applied to the section 2 by introducing one end of the rib 3 into the socket or recess 5, and by sliding the section 1 longitudinally of the section 2 it is obvious that the same will be positioned upon the section 2 in order to register fully therewith and firmly hold the packing over the 40 split or bursted portion of the pipe. The interlocking feature referred to also enables the ready application and separation of the sections of the clamp independently of each other,

which is a desideratum in a clamp of this character and is of especial value in adapting the clamp for use on steam-coils, &c.

While the invention is described as particularly applicable to bursted pipes, it is obvious 50 that the same may be used in connection with pipes wherein rust-holes and pit-holes are present and, in fact, may be employed for the stoppage of leaks of any character. By tapping a hole in clamps constructed in accordance with the present invention the same may be used for pipe-saddles.

Having thus described the invention, what is claimed as new, and desired to be secured by Letters Patent, is—

A pipe-clamp, comprising a pair of complementary sections adapted for separate and independent application to and removal from a pipe, and designed to envelop the latter, one of said sections having at one of its edges a laterally-projecting longitudinally-extending rib, the other section having a flange at one of its edges, said flange forming a socket or recess extending longitudinally of said section and adapted to receive the rib of the first-mentioned section to interlock the sections, the free edge of said flange terminating at a point in rear of the adjacent edge of the body of the section upon which it is formed, whereby a space is provided between the free edge 75 of said flange and the pipe to which the clamp is applied to permit the insertion of the rib of the first-mentioned section into said socket or recess, a plurality of perforated lugs formed upon the opposite edges of the sections, and a 80 plurality of clamping-bolts arranged in said lugs for holding the sections in clamped position upon the pipe.

In testimony whereof I affix my signature in the presence of two witnesses.

OLAUS S. AUGENSEN.
